HENRY H. SMITH, OF WILMINGTON, DELAWARE.

Letters Patent No. 74,859, dated February 25, 1868.

IMPROVED POCKET FOR BILLET-STRAPS.

The Schedule referred to in these Letters Patent and making part of the same.

TO ALL WHOM IT MAY CONCERN:

Be it known that I, HENRY H. SMITH, of Wilmington, in the county of New Castle, and State of Delaware, have invented a new and useful Pocket for Billet-Straps; and I do hereby declare the following to be a full, clear, and exact description of the same, sufficient to enable one skilled in the art to which the invention appertains to make use of it, referreto being had to the accompanying drawings, which form a part of this specification, and in which—

Figure 1 is a perspective view.

Figure 2 is a longitudinal section.

This is a hard-rubber or metallic pocket for receiving the ends of the billet-straps which secure the curtain to the back stay of a carriage. Hard rubber will sufficiently resemble leather to render it a suitable material for the purpose; but if of metal, it will be proper to cover it with leather or a coat of other suitable material.

In the drawings, A represents a part of the back curtain of a carriage, and B one of the back stays. C is the billet-strap attached to the curtain, and fastened by the buckle D to the stay, the end of the billet-strap being secured and protected by the pocket E, which I prefer to make of hard rubber, or it may be made of metal and covered with leather, as represented in the sectional view, fig. 2, where E represents the metal and F the leather covering. When made of hard rubber it will be provided with holes around near its margin, by which to sew it to the stay, and if made of metal they will be similarly punched, ready for the carriage-trimmer.

It will prove a great convenience as a readily-applied pocket, for the purpose of protecting the ends of the billet-straps, which will look much neater than when their ends are allowed to curl up and hang down for lack of support.

The device may be used for other analogous purposes in harness and trunks, for the protection of the ends of straps.

Having described my invention, what I claim as new, and desire to secure by Letters Patent, is—

A pocket, E, of metal, or its equivalent, and at the lower edge of which is a perforated flange, for the purpose specified.

To the above specification of my improvement I have signed my hand, this 26th of December, 1866.

HENRY H. SMITH.
